UNITED STATES PATENT OFFICE

93,968

DESIGN FOR A TABLE

John Mershon Brower, Grand Rapids, Mich.

Application August 20, 1934, Serial No. 52,993

Term of patent 3½ years

To all whom it may concern:

Be it known that I, JOHN MERSHON BROWER, a citizen of the United States, residing at Grand Rapids, in the county of Kent and State of Michigan, have invented a new, original, and ornamental Design for a Table, of which the following is a specification, reference being had to the accompanying drawing, forming part thereof.

The figure is a perspective view of a table showing my new design.

I claim:

The ornamental design for a table, as shown.
JOHN MERSHON BROWER.
